RAILWAY TRACK LINER

John Clark, Walkerton, Ind.

Application March 5, 1943, Serial No. 478,158

6 Claims. (Cl. 254—44)

My invention relates to railway track liners.

As is well known, due to the action of traveling trains, the rails of a track are frequently slightly bent, whereby the track becomes out of alignment. In aligning a track, it is the practice to raise the rails and cross-ties from the roadbed and shift the track laterally to return the same to the proper or aligned position. This work is ordinarily done with track liners. In using the ordinary track liner, it is placed upon the roadbed between the cross-ties and brought into engagement with the rail. The operating lever of the track liner is then moved and the track liner raises and shifts the adjacent portion of the track laterally to return the same to the proper or aligned position. The power employed in raising and aligning the track is also transmitted to the base of the track liner, which compresses the roadbed, and the base becomes slightly sunken in the roadbed, and this uses up a considerable portion of the power, and reduces the throw of the track liner in aligning the track. It frequently happens that one cycle of operation of the track liner is not sufficient to return the track to the proper aligned position, and that the track liner must be operated a number of times. Upon each subsequent cycle of operation of the track liner, it must be bodily shifted in the direction in which the track is to be shifted. When the track liner is bodily shifted and its base assumes a new position, a great deal of the power is again used up in compressing a new portion of the roadbed. This action materially increases the time and labor required to align the track.

In accordance with the present invention, I provide a track liner having an operating unit mounted upon a base and bodily shiftable longitudinally with relation to the base, for a distance equal to the major portion of the length of the rail-engaging lever. By virtue of this arrangement, the base of my track liner may be disposed between the ties at a suitable position adjacent to the rail, and remains in this position, throughout the several cycles of operation of the same. During the first cycle of operation, a considerable portion of the power is taken up by the compression of the roadbed and the sinking of the base therein, after which no further compression occurs. The first cycle of operation may not be sufficient to return the track to the proper aligned position. When this is the case, the operating unit is bodily shifted longitudinally of the base, which now remains stationary, so that the rail-engaging lever is brought nearer to the rail. Upon the next cycle of operation substan-

tially all the power is used in shifting the rail toward or to the aligned position. If necessary, the cycle of operation may be repeated any number of times, until the rail is returned to the proper aligned position, without shifting the base upon the roadbed. My liner is also so constructed that the pressure from the operating lever and the rail-engaging lever is transmitted to the base in a manner to prevent the tilting of the base.

10 In the accompanying drawing forming a part of this application and in which like numerals are employed to designate like parts throughout the same,

15 Figure 1 is a side elevation of a track liner embodying my invention, showing the operating lever in the lowered position.

15 Figure 2 is a central vertical sectional view through the same, showing the operating lever raised,

20 Figure 3 is a plan view of the liner.

Figure 4 is a transverse section taken on line 4—4 of Figure 1.

25 In the drawing, wherein for the purpose of illustration is shown a preferred embodiment of my invention, the numeral 10 designates a preferably flat elongated base, provided at its longitudinal edges with guides 11. These guides are rigidly secured to the base and are disposed above the same. The guides 11 are preferably formed integral with the base 10. The base 10 is provided at its forward end with a transverse stop or rib 12, preferably formed integral therewith, and at its rear end with a stop or rib 13 which may be secured thereto by bolts 14 or the like.

30 The numeral 15 designates a rail-engaging lever, which is preferably formed of a pair of straps or bars 16, spaced as shown. At their forward ends, the bars receive between them a knuckle 17, rigidly secured to a forward foot or slide 18.

35 The bars 16 are pivotally connected with the knuckle 17, by means of a bolt 19 or the like. The bars 16 are preferably longitudinally tapered, decreasing in width forwardly, providing vertically inclined upper edges when the bars are in the

40 lowermost generally horizontal position, and are preferably provided upon their upper edges with notches 20, to receive the edge of the base of the rail. The foot or slide 18 is mounted upon the base 10 and has frictional engagement therewith and operates within the guides 11 and are held thereby upon the base.

45 The numeral 21 designates an operating lever, preferably comprising a socket 22 to receive a handle 23, and the socket is provided with an extension 24, integral therewith. The socket is

disposed between the rear ends of the bars 16 and is pivotally connected therewith by means of a bolt 25 or the like. The forward end of the extension 24 is arranged between a pair of spaced knuckles 26 and is pivotally connected therewith by a bolt 27 or the like. These knuckles are formed integral with a rear foot or slide 28. This foot or slide is mounted upon the upper face of the base 10 and has frictional engagement therewith, and the foot operates within the guides 11 and are held thereby upon the base.

Figure 1 shows the relative positions of the parts at the beginning of the cycle of operation. The operating unit including the rail-engaging lever 15, feet 13 and 28, and operating lever 21 is shiftable with relation to the base 10 longitudinally of the same. With the operating lever 21 in the lowermost general horizontal position, the foot 28 is disposed near but spaced from the stop 13 for a suitable distance, to permit of the rearward sliding movement of the foot 28, when the lever 21 is shifted from the generally horizontal position to a generally perpendicular position. With the parts in these positions, Figure 1, the base 10 extends forwardly beyond the foot 13 for a length preferably equal to the length of the rail-engaging lever 15, or for the major portion of the length of the rail-engaging lever 15.

In the use of the liner, the base 10 is placed upon the roadbed between the ties and beneath the rail, the forward end of the base facing in the direction in which the track is to be shifted. The operating lever and the rail-engaging lever 15 are now in the lowermost position. When the base 10 is arranged beneath the rail, the base should extend for substantially equal distances upon the opposite sides of the rail, so that the weight from the rail, during the lifting and shifting action, will be transmitted to the central portion of the base. As shown in Figure 1, the forward foot 13 and forward end of the rail-engaging lever 15 are adjacent to the central longitudinal axis of the rail. However, the elevation of the upper surface of the roadbed between the ties may vary, and be lower, in which event the rail-engaging lever 15, while in the lowermost position, would be shifted longitudinally with relation to the base in a forward direction so that a higher portion of the inclined edge of the rail-engaging lever would engage the rail. The edge of the base of the rail should be arranged within a notch 20 or above and in alignment therewith. The operating lever 21 is now raised and swings the rail-engaging lever 15 upwardly. When the operating lever 21 is swung upwardly through about 45° its action is to principally raise the rail-engaging lever 15, without shifting the same longitudinally to any considerable extent. When the operating lever 21 is raised for a further extent of about 45° it further raises the rail-engaging lever 15 and shifts it longitudinally forwardly. When the rail-engaging lever 15 is swung upwardly it raises the rail and also exerts a lateral pressure upon the same in the direction of lining the rail. Due to the pivotal connection between the operating lever 21 and the rail-engaging lever 15, the foot 28 slides rearwardly upon the base 10 as the operating lever 21 rises and does not engage the stop 13 until the throw of the lever 21 has been completed. The rail-engaging lever 15 having its rear end pivoted to the lever 21 at 25, and its forward end pivoted at 26, turns upon a point A where it engages with the base of the rail, when the rail is not shifted laterally in the direction of lining after being

raised, thereby causing the foot 13 to slide rearwardly upon the base 10. The action of the rail-engaging lever 15 is to first raise the rail and cross-ties attached thereto and shift the track laterally toward or to the proper aligned position. The force produced by the upward movement of the operating lever 21 is transmitted to the rail-engaging lever 15 and to the base 10. This force packs or compresses the roadbed and causes the base to slightly sink into the roadbed, whereby a considerable portion of the force is taken up by the packing of the roadbed, upon the first cycle of operation of the liner. It is therefore ordinarily necessary to operate the liner for one or more cycles of operation, but no further packing of the roadbed occurs. The base 10 now remains stationary while the operating unit is moved forwardly longitudinally with relation to the base 10, to bring the rail-engaging lever closer to the base of the rail, so that the edge of the base may enter the next rear notch, the operating lever then being in the lowered position. Upon the next cycle of operation, the operating lever is again raised, and since the base 10 does not further compress or pack the roadbed it will not sink therein and all the force employed is utilized in raising the rail and shifting it laterally toward or to the aligned position. Any number of cycles of operation may be employed, and the operating unit is advanced with relation to the base, while the base remains stationary upon the roadbed, prior to the raising of the lever. The feet 13 and 28 are preferably of the same area and have the same frictional engagement with the base. This is important as it serves to transmit the downward force to the base in substantially equal amounts, and at widely spaced points, so that there is no tendency for the base to tilt longitudinally, which would impair the lifting and shifting ability of the liner. The combined frictional engagement of the two feet 13 and 28 with the base is less than the frictional engagement between the base and the roadbed, so that there is no tendency for the base to move upon the roadbed when the lever 21 is raised. Since the base 10 extends forwardly beyond the foot 13 for a distance substantially equal to the length of the rail-engaging lever, the operating unit may be shifted forwardly with relation to the base 10, to bring the rail-engaging lever 15 into engagement with the base of the rail, throughout substantially the entire length of the rail-engaging lever.

In lining the rails, two of my track liners are used at the same time. These track liners are arranged beneath the rails and their forward ends face in the same direction to which the track is to be lined.

It is to be understood that the form of my invention herewith shown and described is to be taken as a preferred example of the same, and that various changes in the shape, size, and arrangement of parts, may be resorted to, without departing from the spirit of my invention or the scope of the subjoined claims.

Having thus described my invention, what I claim is:

1. A railway track liner, comprising an elongated base, guide means on the base extending throughout substantially its entire length, a rail-engaging lever above the base and extending longitudinally thereof, a foot pivotally connected with the forward end of the rail-engaging lever and frictionally engaging the upper face of the base and guided by the guide means, said base

extending forwardly beyond the rail-engaging lever for substantially the major portion of the length of the rail-engaging lever, an operating lever pivotally connected with the rear end of the rail-engaging lever and having its lower end extending beyond such pivotal connection, a foot pivotally connected with the lower end of the operating lever and engaging the upper face of the base and guided by the guide means, the two feet being of substantially the same area and having substantially the same frictional engagement with the base, the operating lever, the rail-engaging lever, and the feet being shiftable as a unit longitudinally of the base with relation thereto for substantially the major portion of the length of the rail-engaging lever so that the rail-engaging lever may engage the rail substantially throughout the major portion of the length of the rail-engaging lever, and stops secured to the opposite ends of the base in the path of travel of the feet.

2. A railway track liner, comprising a vertically swinging rail-engaging lever to be arranged in a lowermost generally horizontal position and then having a vertically inclined upper edge, said lever when swung upwardly serving to raise the rail and exert a lateral force upon the rail in the direction of lining the rail, a base beneath and extending longitudinally of the rail-engaging lever, an operating lever pivotally connected between its ends with the rear end of the rail-engaging lever, a rear foot pivotally connected with the free end of the operating lever and mounted upon the base, a forward foot pivotally connected with the forward end of the rail-engaging lever and mounted upon the base, the base extending forwardly beyond the forward foot when the rail engaging lever is in the lowermost and rearmost position and the rear foot is spaced from the rear end of the base, the base being free from obstruction forwardly of the rear foot so that the forward and rear feet are shiftable forwardly upon the base when the rail-engaging lever is in the lowermost position to bring a rear portion of the upper inclined edge of the rail-engaging lever into engagement with the rail.

3. A railway track liner, comprising a vertically swinging rail-engaging lever to be arranged in a lowermost generally horizontal position and then having a vertically inclined upper edge, said lever when swung upwardly serving to raise the rail and exert a lateral force upon the rail in the direction of lining the rail, a base beneath and extending longitudinally of the rail engaging lever, said base being at least twice as long as the major portion of the length of the rail-engaging lever, an operating lever pivotally connected between its ends with the rear end of the rail-engaging lever, a rear foot pivotally connected with the free end of the operating lever and mounted upon the base, a forward foot pivotally connected with the forward end of the rail-engaging lever and mounted upon the base, the base extending forwardly beyond the forward foot for at least the major portion of the length of the rail-engaging lever when the rail-engaging lever is in the lowermost and rearmost position and the rear foot is spaced from the rear end of the base, the base being free from obstruction between its ends so that the forward and rear feet are shiftable forwardly upon the base when the rail-engaging lever is in the lowermost position to bring the upper inclined edge of the rail-engaging lever into engagement with the rail throughout the

major portion of the length of the rail-engaging lever, and means to guide the forward and rear feet when shifted longitudinally of the base.

4. A railway track liner, comprising a vertically swinging rail-engaging lever to be arranged in a lowermost generally horizontal position and then having a vertically inclined upper edge, said lever when swung upwardly serving to raise the rail and exert a lateral force upon the rail in the direction of lining the rail, a base beneath and extending longitudinally of the rail-engaging lever, said base being at least twice as long as the major portion of the length of the rail-engaging lever, an operating lever pivotally connected between its ends with the rear end of the rail-engaging lever, a rear foot pivotally connected with the free end of the operating lever and mounted upon the base, a forward foot pivotally connected with the forward end of the rail-engaging lever and mounted upon the base, the base extending forwardly beyond the forward foot for at least the major portion of the length of the rail-engaging lever when the rail-engaging lever is in the lowermost and rearmost position and the rear foot is spaced from the rear end of the base, guide means for the forward and rear feet and carried by the base and extending throughout the major portion of the length of the base, stop elements secured to the base near its forward and rear ends, the base being free from obstruction between the stop elements so that the forward and rear feet are shiftable forwardly upon the base for a distance of at least the major portion of the length of the rail-engaging lever when the rail-engaging lever is in the lowermost position to bring rear portions of the upper inclined edge of the rail-engaging lever into engagement with the rail.

5. A railway track liner, comprising a vertically swinging rail-engaging lever to be arranged in a lowermost generally horizontal position and then having a vertically inclined upper edge, said lever edge being provided with longitudinally spaced notches, said lever when swung upwardly serving to raise the rail and exert a lateral force upon the rail in the direction of lining the rail, a base beneath and extending longitudinally of the rail-engaging lever, said base being at least twice as long as the major portion of the length of the rail-engaging lever, an operating lever pivotally connected between its ends with the rear end of the rail-engaging lever, a rear foot pivotally connected with the free end of the operating lever and mounted upon the base, a forward foot pivotally connected with the forward end of the rail-engaging lever and mounted upon the base, the base extending forwardly beyond the forward foot for at least the major portion of the length of the rail-engaging lever when the rail-engaging lever is in the lowermost and rearmost position and the rear foot is spaced from the rear end of the base, guide means for the forward and rear feet and carried by the base and extending throughout the major portion of the length of the base, stop elements secured to the base near its forward and rear ends, the base being free from obstruction between the stop elements so that the forward and rear feet are shiftable forwardly upon the base for a distance of at least the major portion of the length of the rail-engaging lever when the rail-engaging lever is in the lowermost position to bring rear portions of the upper inclined edge of the rail-engaging lever into engagement with the rail.

6. A railway track liner, comprising a vertically swinging rail-engaging lever to be arranged in a lowermost generally horizontal position and then having a vertically inclined upper edge, said lever when swung upwardly serving to raise the rail and exert a lateral force upon the rail in the direction of lining the rail, a base beneath and extending longitudinally of the rail-engaging lever, said base being substantially twice as long as the rail-engaging lever, an operating lever pivotally connected between its ends with the rear end of the rail-engaging lever, a rear foot pivotally connected with the free end of the operating lever and mounted upon the base, a forward member pivotally connected with the forward end of the rail-engaging lever and mounted upon the base, the base extending forwardly beyond the

5 forward member for substantially the length of the rail-engaging lever when the rail-engaging lever is in the lowermost and rearmost position and the rear foot is spaced from the rear end of the base, means mounted upon the base to guide the rear foot and forward member, stop means 10 arranged near the ends of the base, the base being free from obstruction between the stop means so that the forward member and rear foot are shiftable forwardly upon the base for substantially the length of the rail-engaging lever when the rail-engaging lever is in the lowermost position to bring rear portions of the upper inclined edge of the rail-engaging lever into engagement with the rail.

JOHN CLARK.
